being coupled by an elbow such as to form between them a whole multiple angle of

$$310 \times \frac{\lambda}{d}$$

degrees.

In the accompanying drawing, Figs. 1 and 2 illustrate, respectively, by way of example, a coupling device according to the present invention, and its application to a distance connection. 10

Fig. 1 shows a coupling device between two lengths l and l' of circular cross-section rectilinear guides of diameter d , this device consisting of a single elbow 2 such that the axes of the two rectilinear lengths make an angle θ between them determined as indicated above.

Fig. 2 is a diagram of a connection between two points A and B between which there is an obstacle M. This connection is secured by means of four rectilinear lengths or portions, AC, DE, FG and HB, connected together by means of elbows, CD, EF, GH, as described in connection with Fig. 1, and arranged according to a line such that the successive lengths form between angles θ_1 , θ_2 , θ_3 , all full multiples of

$$310 \times \frac{\lambda}{d}$$

degrees.

If the diameter of the guides and a wave length are given, and if we have, for example

$$\frac{\lambda}{d} = \frac{1}{10}$$

it is possible to give to each of the angles one of the values 31° , 62° , 93° and 124° .

The invention claimed is:

1. In a hollow-pipe type wave guide having a circular cross-section of diameter d and adapted to propagate TE_0 electromagnetic waves having

a wave length λ in free space, two portions of rectilinear wave-guides, and one kneeed portion of guide arranged between said rectilinear portions, the knee of said kneeled portion of guide forming an angle multiple of

$$310 \times \frac{\lambda}{d}$$

degrees, λ and d being expressed with any same unit.

2. In a hollow-pipe type wave-guide having a circular cross-section of diameter d and adapted to propagate TE_0 electromagnetic waves having a wave-length λ in free space, two portions of rectilinear wave-guides, and a plurality of kneeled portions of guide arranged between said rectilinear portions, the angles of the knees of said kneeled portions being such that the longitudinal axis of said two rectilinear portions form between them an angle multiple of

$$310 \times \frac{\lambda}{d}$$

degrees, λ and d being expressed with any same unit. 25
